DESIGN FOR A GAME BOARD

Wilbur M. Enfield, San Francisco, Calif.

Application August 28, 1945, Serial No. 121,677

Term of patent 7 years

(Cl. D34—5)

To all whom it may concern:

Be it known that I, Wilbur M. Enfield, a citizen of the United States of America, residing at San Francisco, in the county of San Francisco and State of California, have invented a new, original, and ornamental Design for a Game Board, of which the following is a specification, reference being had to the accompanying drawing, forming part thereof.

The drawing is lined for color.

I claim:

The ornamental design for a game board, as shown and described.

WILBUR M. ENFIELD.
